UNITED STATES PATENT OFFICE

1,969,409

BOTTLE SHIPPING CRATE

William C. Krause, Milwaukee, Wis.

Application August 7, 1933, Serial No. 684,039

2 Claims. (Cl. 217—36)

This invention appertains to crates and more particularly to a novel case or the like commonly employed for receiving bottles during the handling or shipping thereof.

5 Bottle cases are usually constructed from a series of slats or superimposed flat boards, which form the side and end walls of the case. These slats or boards are secured together by the use of angle irons and rivets are employed for fastening the slats or boards to the angle irons. These cases are subjected to extreme rough handling and generally the same are piled one upon the other. Thus, considerable stress is placed upon the rivets and the boards or slats soon work loose from 10 the rivets and are pushed down one upon the other causing the entire disintegration of the case in a comparatively short time.

Many attempts (see my prior Patent No. 1,702,874, issued to me February 19, 1929) have 15 been made to overcome the above difficulties, but to my knowledge none of these attempts have been successful to the most desirable point.

It is, therefore, one of the salient objects of my invention to provide novel means for constructing the angle irons whereby the slats or boards will be correctly spaced for ventilation purposes and whereby stress will be eliminated 20 on the rivets, when the cases are stacked one upon the other, so as to effectively prevent the slats or boards from breaking away from the rivets.

Another important object of my invention is to provide a novel means for constructing the corner irons whereby any stress or force placed 25 upon the top or bottom face of the crate will be effectively distributed from the top of the crate to the bottom, the novel means of forming the corner irons permitting the easy and quick placing of the slats in position without undue difficulty 30 on the part of the workmen assembling the crates.

A further important object of my invention is the provision of a bottle case or crate having 35 novelly constructed corner irons for receiving and connecting the slats or boards forming the side and end walls of the case, the irons having struck out therefrom inwardly directed horizontally disposed lips or loops, which lips or loops are adapted to be positioned between the slats and to extend from one slat to the other, whereby the slats will 40 not only be effectively spaced, but whereby any force exerted on the top or bottom slats or boards will be transmitted directly from one slat or board to the next, so that said force will be distributed to the ground or other support on which 45 the case is positioned.

A still further object of my invention is to provide a novel bottle case of the above character, which will be durable and efficient in use, one that will be simple and easy to manufacture and one which can be placed upon the market at a 50 low cost.

With these and other objects in view, the invention consists in the novel construction, arrangement and formation of parts, as will be hereinafter more specifically described, claimed 55 and illustrated in the accompanying drawing, in which:—

Figure 1 is a fragmentary end elevation of a bottle case constructed in accordance with my invention illustrating the use of the improved corner iron.

Figure 2 is a vertical section through the case taken on the line 2—2 of Figure 1 looking in the direction of the arrows, illustrating the novel formation of the lips or loops struck out from the 75 corner iron.

Figure 3 is a detail horizontal section taken on the line 3—3 of Figure 1 looking in the direction of the arrows, illustrating the construction of the lips or loops struck out from the corner iron.

Referring to the drawing in detail, wherein similar reference characters designate the corresponding parts throughout the several views, the letter A generally indicates a fragment of a bottle case or crate constructed in accordance with my 85 invention. As shown, the case A embodies side and end walls 5 and 6 each of which are formed from a plurality of superimposed slats or boards 7.

The side and end walls 5 and 6 and slats thereof are connected by means of corner irons 8. 90 These angle irons 8 may be formed from sheet metal of the desired gauge and are of an angle shape in cross section, and each includes like right-angularly extending flanges 9 and 10. The upper and lower ends of the angle or corner irons 95 8 are provided with in-turned extensions 11 and 12 for engaging over the upper and lower edges of the crate and may be otherwise treated to form an effective support such as is illustrated in my prior patent heretofore referred to.

The angle or corner irons can also be provided with offset projections 13 at their upper ends for the purpose of interengaging the lower edge of an adjacent crate stacked thereon. Rivets or the like 14 extend through the flanges 105 of the corner irons and through the slats or boards 7 forming the side and end walls of the case.

The above description of the case can be considered as exemplifying an ordinary type of case 110

or that type of case shown in my mentioned patent.

In accordance with the present invention, I strike out from the flanges 9 and 10 of the corner irons at spaced points inwardly directed lips or loops 15. These lips or loops are formed by slitting the metal of the corner irons at spaced parallel points and forcing that portion of the metal between the pairs of slits inwardly, as clearly shown in the various figures of the drawing.

As illustrated more clearly in Figure 2, these lips or loops 15 occupy the entire height of the space between the different slats or boards 7 and thus, the lips or loops extend from one slat to the other giving a substantial metal-to-metal contact throughout the entire height of the case. Obviously, when a weight or force is placed on top or bottom of the crate, this force will be transmitted through the medium of the lips from one slat to the other and thence, to the ground or other support on which the crate may be placed. This in effect gives a pillar construction in each corner of the case and effectively eliminates all stress on the rivets 14 which eliminates the tearing away of the slats or boards from said rivets.

If lips were struck out entirely from the corner irons and merely placed into engagement with the lower edges of the slats, obviously these lips would bend when undue stress was placed upon the slats and thus, the stress will again be transmitted to the rivets.

In my improved construction, however, where the lips or loops 15 engage the adjacent edges of the upper and lower slats, the force is effectively transmitted from one slat to the other through said loops or lips 15.

From the foregoing description, it can be seen that I have provided a novel corner iron construction for crates which will insure the maximum longevity to the crates and at the same time facilitate the construction thereof in that the lips form an effective means for properly spacing the slats one from the other and thus, facilitate the positioning of the slats.

Changes in details may be made without departing from the spirit or the scope of this invention, but what I claim as new is:—

1. As a new article of manufacture, a corner iron for a bottle case of angle shape in cross section including right angularly extending flanges, and loops struck out from said flanges at spaced parallel points, said loops being disposed in horizontal plane and constituting integral sections of metal forced inwardly from the flanges between spaced parallel slits formed in said flanges, the upper and lower edges of the loops forming flat, slat abutting and supporting faces.

2. In a bottle case including side and end walls, each consisting of a plurality of superimposed spaced boards, corner irons connecting the meeting ends of the walls together, rivets extending through the flanges of the corner irons and the boards, and lips struck out from the flanges of the corner irons extending into the spaces between the boards, said lips constituting sections of metal forced inwardly from the flanges of the corner irons between spaced parallel slits formed in said corner irons, the upper and lower edges of the lips being parallel and constituting abutting faces engaging the upper and lower edges of adjacent boards.

WILLIAM C. KRAUSE.
